UNITED STATES PATENT OFFICE.

ALBERT OBERHEIM, OF OGDEN, UTAH.

RAZOR AND GUARD THEREFOR.

1,077,545.

Specification of Letters Patent.

Patented Nov. 4, 1913.

Application filed April 1, 1912. Serial No. 687,581.

To all whom it may concern:

Be it known that I, ALBERT OBERHEIM, a citizen of the United States, and a resident of Ogden, in the county of Weber and State of Utah, have invented a new and Improved 5 Razor and Guard Therefor, of which the following is a full, clear, and exact description.

This invention relates to improvements in 10 razors of the safety type and guards therefor, and has for an object to provide an improved structure which may be easily assembled and disassembled, and will when assembled present a simple effective construction.

Another object of the invention is to provide a razor blade formed with a guiding 15 projecting bead and a guard co-acting therewith formed with engaging members designed to fit over the end of the razor blade and in the opposite sides of said bead for holding the guard properly in place.

A still further object of the invention is the provision of a razor structure formed 20 with a blade having a longitudinal bead and a movable sleeve. This structure co-acts with a removable guard structure formed with the usual guarding fingers and with a projecting tongue for engaging said sleeve 25 and a pair of spaced fingers for engaging the blade on each side of the bead, whereby the guard is held rigidly in place.

In carrying out the objects of the invention, a blade is provided having preferably 30 cutting edges on each side, the blade being also preferably hinged to any suitable supporting handle designed to protect the blade when the same is not in use. The blade is constructed with a central longitudinal bead 35 on one side and flat on the opposite side so as to accommodate a flat guard. The guard is formed with a tongue extending from one end for engaging the slidable sleeve arranged on the reduced part of the razor 40 blade and with a pair of spaced fingers at the opposite end adapted to engage the blade on each side of the bead, whereby the guard is held rigidly in place and either side of the blade may be used, the guard being 45 formed with the usual guarding fingers on each side.

A practical embodiment of the invention is represented in the accompanying drawings forming a part of this specification, in which 50 similar characters of reference indicate corresponding parts in all the views.

Figure 1 is a perspective view of an embodiment of the invention; Fig. 2 is a top plan view of an embodiment of the invention, the handle being broken away; Fig. 3 is an end view of the structure shown in Fig. 2; Fig. 4 is a section through Fig. 2 on the line 4—4; Fig. 5 is an end view of the guard removed; Fig. 6 is a side view of the structure shown in Fig. 1, the same being 60 shown in a closed position and on a slightly enlarged scale; Fig. 7 is a top plan view of the razor blade with part of one end thereof removed, a strop guard being shown in connection therewith; and Fig. 8 is a section 65 through Fig. 7 on the line 8—8.

Referring to the accompanying drawings by numerals, 1 indicates a pivotal casing or handle structure, 2 a razor, and 3 the guard. The handle structure 1 may be made in any 70 desired manner and pivotally secured at 4 to the shank 5 of the blade 2, which is formed with cutting edges 6 and 7, and a bead 8. The side of the blade 2 opposite the bead 8 is made preferably flat so as to accommodate 75 the guard 3 which is formed flat. The guard 3 is formed with the usual guard fingers 9 and 10, and with a centrally arranged extending tongue 11 at one end and a pair of spaced tongues 12 and 13 at the opposite 80 end. The tongue 11 is adapted to extend parallel with the shank 5 so that the sleeve 14 slidingly mounted on the shank 5 may be slipped over the tongue 11, binding the same 85 tightly to the shank 5. The spaced tongues 12 and 13 are arranged to be positioned on each side of the bead 8 when the guard 3 is in use. By the arrangement of tongues 12 and 13 engaging the bead 8, and the tongue 11 engaging the sleeve 14, the guard is held 90 rigidly in place and either of the edges 6 or 7 may be used.

When it is desired to strop the blade 2, the guard 3 is removed and the stropping guard 15 is slipped over one edge of the 95 blade 2 so that in moving the razor back and forth over the strop the under edge will engage the same and the opposite edge will be prevented from cutting into the strop. The guard 15 is formed with a pressed out portion 16 which encircles the bead 8 and assists in holding the guard 15 in position, the guard 15 being made of preferably resilient material and formed so as to resiliently clamp against the blade 2. After one edge 100 of the razor 2 has been stropped, the guard 15 may be removed and placed over the

stropped edge and the opposite edge stropped in the usual manner. By this construction and arrangement of strop guard, a double edged razor may be provided and yet may be freely stropped in the usual manner of razors having a single cutting edge.

Having thus described my invention I claim as new and desire to secure by Letters Patent:—

10. In a razor of the class described, the combination with a blade provided with a handle and having a longitudinally positioned bead, of a guard formed with a pair of

space bent-over fingers adapted to fit over the end of said blade and each side of said bead, and means for connecting said guard to said blade on the end opposite to said fingers. 15

In testimony whereof I have signed my name to this specification in the presence of 20 two subscribing witnesses.

ALBERT OBERHEIM.
